UNITED STATES PATENT OFFICE.

WILLIAM E. T. MERRILL AND ADAM LEPPER, OF PHILADELPHIA,
PENNSYLVANIA.

DESIGN FOR A HAM-BOILING WRAPPER.

SPECIFICATION forming part of Design No. 29,510, dated October 18, 1898.

Application filed August 9, 1898. Serial No. 688,216. Term of patent 3½ years.

To all whom it may concern:

Be it known that we, WILLIAM E. T. MERRILL and ADAM LEPPER, citizens of the United States, residing in the city and county of Philadelphia, State of Pennsylvania, have invented and produced a new and original Design for Ham-Boiling Receptacles or Wrappers, of which the following is a specification, reference being had to the accompanying drawings, forming part thereof.

The leading feature of our design for a ham-boiling wrapper is a wrapper with lacing devices within the border thereof, arranged as shown.

Figure 1 represents a face view of a ham-boiling wrapper embodying our design. Fig. 2 represents a section thereof on line $x\ x$, Fig. 1.

A designates a wrapper, and B designates lacing devices on said wrapper, said devices 20 being separated at intervals and set back from the border of the wrapper and arranged in the form of a many-sided figure.

Having thus described our invention, what we claim as new, and desire to secure by Letters Patent, is—

The design for a ham-boiling wrapper, substantially as described and claimed.

WILLIAM E. T. MERRILL.
ADAM LEPPER.
